OVER-DOOR INSECT REPELLING FAN

Henry Zeiler, 1055 E. 1st St., Loveland, Colo.

Filed May 29, 1961, Ser. No. 65,399

Term of patent 14 years

(Cl. D62—4)

1.

2.

FIG. 1 is a top plan view of an over-door insect repelling fan showing my new design;

FIG. 2 is a front elevational view thereof;

FIG. 3 is a side elevational view thereof;

FIG. 4 is a rear elevational view thereof; and

FIG. 5 is a reduced scale perspective view thereof looking upwardly at the front and one side of the over-door insect repelling fan.

I claim:

The ornamental design for an over-door insect repelling fan, as shown.
